UNITED STATES PATENT OFFICE.

EMILE AUGUSTIN BARBET, OF PARIS, FRANCE.

PROCESS FOR EXTRACTING BENZOLS FROM HEAVY OILS.

Application filed March 21, 1921. Serial No. 454,214.

(GRANTED UNDER THE PROVISIONS OF THE ACT OF MARCH 3, 1921, 41 STAT. L., 1313.)

To all whom it may concern:

Be it known that I, EMILE AUGUSTIN BARBET, a citizen of the French Republic, and residing at Paris, France, have invented a 5 certain new and useful Improved Process for Extracting Benzols from Heavy Oils, for which I have filed applications in France, Sept. 5, 1913, Patent No. 473,082; Great Britain, May 17, 1916, Patent No. 100,493; 10 Belgium, May 16, 1916, Patent No. 275,692; Italy, May 17, 1916, Patent No. 128, Vol. 458; and in Spain, Oct. 30, 1917, Patent No. 65,646; of which the following is a specification.

15 This invention relates to treating heavy oils which have been employed for the separation from coke oven and like gases of the volatile constituents contained in them.

It may be stated that a known method 20 involves the thorough washing of coke oven gas, and other analogous gases, with a heavy non-volatile tar oil. This absorbs the substances which exist as vapors in said gases, and the recovery of such absorbed materials, 25 in separated condition, forms the object of the present invention.

According to the invention, the more volatile of the absorbed materials are, by indirect heating, distilled off and separated 30 into their several components, after which live or superheated steam is injected into the residual oil in order to expel the naphthalene therefrom.

The apparatus, according to the invention, 35 preferably comprises the individual features and arrangements hereinafter referred to.

The process and apparatus will be described with reference to the accompanying 40 drawings which show by way of example an arrangement of plant which may be employed.

The figure is a general view of the apparatus. The benzolated oils which are contained in an upper reservoir, not shown in 45 the drawing, enter through the pipe 1. Their rate of delivery is regulated by a calibrated cock R having a graduated dial or quadrant.

50 Thence they pass into the tubes of the heat exchanger A wherein they are partially heated by the outgoing heavy oils from which the benzols have been extracted. After passing out from A through the pipe 2, they

serve as a cooling liquid for the coil condenser C whose function is hereinafter described.

The benzolated oils becoming hotter and hotter, pass out from C through the pipe 3, and they pass through the second tubular 60 exchanger B, and thence through the pipe 4 they enter finally the distilling column D.

The top plate on to which the hot benzolated oils are delivered, is a sort of "reservoir plate" 25 where the liquid finally assumes a complete equality of temperature with the vapours of distillation. The vapours pass through the reservoir plate by way of a suitable number of "chimneys" 26. In this plate the oils begin to lose a small 70 proportion of their lighter components.

The oils descend through an overflow 5 on to the hooded plates D which are plates similar to those of all continuous distilling columns; these plates are not numerous. 75 Below these there are several vaporizing plates E. The plates E contain a considerable volume of liquid and are provided with a powerful live steam coil 27 whose temperature must not be less than, and is preferably above 160° C. As a matter of fact a high temperature is required not only for expelling the whole of the benzene, but especially for extracting at the same time the heavier benzols, the toluene, xylol and cumene. The oil descends successively from one vaporizing plate to the next, and should arrive in a completely exhausted state on the 80 last plate.

From the last plate E the boiling oil 90 passes through the siphon pipe 6 onto a last series of distilling plates F intended for extracting the naphthalene from the said oil. The naphthalene which has a boiling point of about 216° C. can only be expelled 95 by agitation with steam which operates by direct mechanical action. It is advisable to employ the steam as dry and as hot as possible. The exhaust steam of an engine may be used with advantage, so as to utilize its latent heat, but preferably after passing it through a live steam tubular superheater before injecting it into the bottom of F.

The mixture of steam and naphthalene vapour passes out through the pipe 7 into the coil 7^a in the condenser C. It is necessary to liquefy the naphthalene, but it must not be allowed to congeal, and for this purpose 105

instead of using water as a condensing liquid, use is made as above stated of the benzolated oil which has already been rendered lukewarm to a great extent in the heat exchanger A. As a precaution, and mainly for starting, there is arranged at the centre of the condenser C a small steam coil 28 for heating the condenser to the desired point before beginning the distillation of the 10 naphthalene.

The mixture of water and naphthalene which is condensed in C, passes out through 9 into a continuous decanting device serving as a "Florentine vessel" separating funnel.

15 The two liquids form two distinct layers which can be caused to discharge continuously and separately.

The heavy oil deprived of naphthalene issues from the bottom of F through the 20 siphon pipe 10, passes through the heat exchanger B, and then passes through the pipe 11 to the other heat exchanger A where it restores almost the whole of its heat to the entering benzolated oil. Then through the 25 pipe 12 it passes to a water cooler G. This cooler is filled with crushed quartz. The heavy oil which is still lukewarm descends through the interstices of the quartz, whilst the cold water ascends in counter current 30 contact therewith. There is therefore a cooling action by direct contact, that is to say, with maximum efficiency, and the regenerated and cooled oil passes finally out through the pipe 13 on its way back to the 35 apparatus in which it is caused to absorb the benzols contained in the oven gases.

Referring again to the complex benzol vapours which are given off at the top of the distilling column D, it is now necessary to separate them into their components, 40 in other words, to rectify them.

The benzolated vapours pass out from D through the pipe 14 and enter the bottom of the rectifying column H.

45 The fractionating takes place according to the ordinary principles of every rectification process; the plate column H is surrounded by a water condenser K and a cooler L. The liquid condensed in K and a 50 portion of that of L return through the pipes 16 and 17 to the top of the column H. This is what is known as the reflux, and this reflux constituting a clarifying or washing liquid, refines the benzolated vapours 55 which are bubbling up through it, whilst the reflux itself becomes freed from its more volatile elements. In this manner there is produced a systematic and very sharply defined classification.

60 Right at the beginning the more volatile parts consisting of carbon disulphide and other compounds of low boiling point having a garlic-like odour, are drawn from the cooler L through the pipe 18.

65 A certain proportion of the reflux, which

has already been boiled up again on three or four plates, is extracted from the upper part of the column through the pipe 19. This is benzene, and the boiling up again to which it has just been subjected, has freed it 70 from the carbon disulphide and the products of onion-like odour. It is cooled in the cooler M and then passes into a test glass N having a constant regulation discharge of the known type. 75

Lower down, toluene is extracted in the same manner through the pipe 20. Still further down, the xylol is extracted through the pipe 21, and from the base of H the heaviest distilled products are drawn through 80 the pipe 22. These last three fractions are cooled in the triple-coil cooler P, and they pass out finally through three test glasses of constant regulation similar to the test glass N. 85

Thermometers T and T', mounted on the rectifying column H, allow the operator to regulate with great accuracy the volume of the respective fractions which pass through 19, 20, 21 and 22. 90

If too great a proportion of naphthalene is found in the draw off pipe 22, then instead of sending this liquid into the cooler P, it is caused to return through the pipe 23 into the naphthalene column F, or it may be 95 connected directly to the pipe 9 by means of the pipe 24.

The heating of the column D is regulated by means of a steam regulator V of variable 100 adjustment of the known type.

Having now described my invention, what I claim as new and desire to secure by Letters Patent is:—

A process which comprises progressively 105 heating a mixture including a heavy non-volatile oil containing absorbed materials normally present as vapors in coke oven gas, first by the heat of the out-going stripped oil and by the vapors carrying naphthalene 110 coming from the high heating of such oil as set forth below, thereafter running the somewhat preheated oil through a column still including a rectifying column and first heating the same by indirect steam heat to about 160° C., while drawing off the evolved 115 vapors of the lower part of the rectifying column through which such vapors rise, further heating the unvolatilized oils by blowing thereinto superheated steam capable of raising the temperature of said oils to vaporize the naphthalene, and drawing off the 120 mixed vapors containing naphthalene and superheated steam and cooling such vapors by indirect cooling with the lukewarm incoming oils, such vapors being kept separate 125 from those passed through the rectifying column.

In testimony whereof I have signed my name to this specification.

EMILE AUGUSTIN BARBET.
